(57) **CLAIM**

The ornamental design for a glasses and case set, as shown and described.

DESCRIPTION

FIG. 1 is a perspective view of glasses;

FIG. 2 is a front view of the glasses of FIG. 1;

FIG. 3 is a rear view of the glasses of FIG. 1;

FIG. 4 is a left side view of the glasses of FIG. 1;

FIG. 5 is a right side view of the glasses of FIG. 1;

FIG. 6 is a top view of the glasses of FIG. 1;

FIG. 7 is a bottom view of the glasses of FIG. 1;

FIG. 8 is a rear view of the glasses of FIG. 1 in a second configuration;

FIG. 9 is a perspective view of the glasses of FIG. 1 in a third configuration;

FIG. 10 is another perspective view of the glasses of FIG. 1 in a fourth configuration;

FIG. 11 is a perspective view of a case;

FIG. 12 is a front view of the case of FIG. 11;

FIG. 13 is a rear view of the case of FIG. 11;

FIG. 14 is a left side view of the case of FIG. 11;

FIG. 15 is a right side view of the case of FIG. 11;

FIG. 16 is a top view of the case of FIG. 11;

FIG. 17 is a bottom view of the case of FIG. 11;

FIG. 18 is a perspective view of the case of FIG. 11 in a state of use;

FIG. 19 is another perspective view of the case of FIG. 11 in a second state of use;

FIG. 20 is a perspective view of a glasses and case set in a state of use;

FIG. 21 is a perspective view of the glasses and case set in a second state of use; and,

FIG. 22 is another perspective view of the glasses and case set in a third state of use.
